COIN CONTROLLED MECHANISM FOR GAS
AND SIMILAR METERSErnest William Smith, London, and Arthur
Charles, Streatham Vale, London, EnglandApplication April 30, 1934, Serial No. 723,270
In Great Britain June 28, 1932

9 Claims. (Cl. 194—72)

This invention relates to coin-actuated mechanism for gas and similar meters wherein the coins are retained in the coin holder by pressure exerted in a direction transverse to that of the movement of a coin entering the coin holder, which coin actuates a striker to engage a measuring wheel, and especially to coin holders of the kind adapted to operate with coins of different values and provided with a coin slot for each value.

The invention is especially applicable to coin holders such as are described in the specification of the co-pending application Serial No. 668,950, filed May 2, 1933, of which this application is a division in part.

The invention has for its object to ensure the rejection from the coin holder of a coin of small size that may accidentally be inserted in a coin slot intended to receive coins of large size.

The invention has further for its object to provide means whereby the entry of the smaller size coin into the coin pocket may be prevented.

The invention has also for its object to provide a construction of mechanism whereby the accidental insertion of a coin of a size other than that for which the coin pocket is intended is prevented while a deliberate attempt to insert such a coin by depressing the striker may result, according to the size of the coin, in the coin being received into the coin pocket without the striker being engaged with the measuring wheel, so that if the coin holder be rotated the coin is lost without an equivalent supply of the commodity being received.

According to the invention the coin pocket or coin space adapted to receive a coin of a determined size has the surface by which pressure is applied to the coin therein formed by a movable element having a movement of limited range distinct from and independent of the movement of the striker and of such shape that on the introduction of a coin smaller than the determined size the extent of the movement of the said element is insufficient to result in movement of the striker or to ensure a stable position of the coin under the pressure applied, with the result that the striker remains without movement and the element functions to reject the coin from the coin slot, while on the introduction of a coin of the determined size the said element is depressed to an extent to result in movement of the striker and is moved into a position to render the pressure no longer effective to reject the coin.

According to the invention, moreover, the movable or ejector element is advantageously pivoted

to the striker at a position immediately behind the coin slot and is of such form that it normally presents an inclined or curved surface to a coin introduced into the coin slot.

According to the invention, moreover, the movable element may be provided as a sector plate mounted under the action of a spring and adapted to co-operate with a stop limiting its movement and maintaining it normally in the position to obstruct the entrance of the coin, the edge of the plate being of such form that on the insertion of a coin of the proper value the element is depressed against the action of the opening to exert upon the coin a pressure which is normal to the axis of the coin holder.

According to the invention, moreover, the movable or ejector element forming the bottom of the coin pocket may be constrained to move transversely to the path of a coin entering the coin pocket and during such movement to present a surface opposing the entry into the coin pocket of all coins smaller than the coin for which the coin pocket is intended and, on the insertion into the coin pocket of a coin of the correct size, to move out of the path of the coin under the pressure exerted by the coin.

According to the invention, moreover, the movable element, which may be pivoted to the striker or like member operated by a coin on its entry into the coin pocket, may be constrained against pivotal movement except when the striker plate or equivalent member is moved by a coin of the size for which the coin pocket is intended.

According to the invention, also, the movable element may be disposed adjacent one of the walls of the coin holder bounding the coin pocket or an equivalent relatively stationary surface, and the constraint against pivotal movement may be applied by guiding or cam surfaces or slots and co-operating projections or stops provided respectively on the two relatively movable parts.

Again, according to the invention, the movable element may co-operate with a stop member adapted to restrict the movement of the element in such manner that when a coin of a size smaller than that for which the coin pocket of the coin holder is intended is pressed into the slot the movable element moves only so far as is permitted by the stop member and by reason of its form and the pressure it exerts upon the coin rejects the latter from the slot, while ensuring that, on the insertion through the slot of a coin of the size for which the coin pocket is intended, the consequential movement which the movable element makes in common with the striker suffices to

carry the movable element out of the range of the stop member and to permit the element to complete its movement distinct from that of the striker so that it may take up the position required for the retention of the coin in the coin pocket.

If, therefore, the attempt be made to insert, for example, a half-penny into the slot intended for a penny by deliberate movement of the movable element and the striker to free the element of the restraint imposed by the stop member, while the movable element tends to take up the position for retention of the coin, by reason of the smaller diameter of the coin, the striker is not moved to the extent to engage or remain in engagement with the measuring wheel. Thus, although the rotation of the coin holder is ineffective, the coin is discharged into the coin receptacle.

According to the invention, moreover, in the case of a coin holder provided with a striker adapted for a sliding movement in relation to the coin pocket, the movable element is mounted upon the striker in such manner as to have a limited movement in relation thereto and the stop member is mounted upon the coin holder at a position such that when the movable element is caused to carry out its movement independently of the movement of the striker, such movement is arrested by engagement of the movable element or a part thereon with the stop member, whereas when the movable element is caused also to partake in the movement of the striker it is carried into a position in which it may execute the movement relatively to the striker without restraint from the stop member.

The invention further comprises the constructional features hereinafter described.

The invention is illustrated, by way of example, in the accompanying drawing.

Figure 1 is a sectional side elevation of a coin holder mechanism provided according to the invention.

Figure 2 is a rear elevation of the coin holder partly in section.

Figure 3 is a sectional plan view of the coin holder mechanism.

Figure 4 is a sectional side elevation of a modified construction of coin-holder mechanism according to the invention.

Figure 5 is a side elevation corresponding to Figure 4.

Figure 6 is a side elevation of a further modified construction of coin-holder mechanism according to the invention.

In carrying the invention into effect according to the construction represented in Figures 1 to 3 of the accompanying drawing, the coin holder mechanism is constructed substantially on the lines described and illustrated in the specification and drawing of application Serial No. 668,950, but means are provided according to the invention to permit of the rejection from the coin holder of a coin of small size accidentally inserted into the slot intended for coins of large size. The transversely disposed part g^4 carried by the striker g for the coin of large size, such as a penny, is reduced in thickness to the extent corresponding to the width of the coin pocket or coin space required to receive a penny, and upon the said part there is pivotally mounted the movable or ejector element k which serves to take the place of the portion of the transversely disposed part that has been omitted. The movable or ejector element is con-

veniently provided as a sector-like plate that is pivoted at k^1 to the transversely disposed part in a position adjacent the disc b by which the coin holder is carried. The angular movement of the said element about its pivotal point is determined by a slot k^2 struck about the pivotal point as centre, which slot engages a pin k^3 also mounted in the transversely disposed part before referred to. The form of the upper or operative edge k^4 of the element k is such that when the element is depressed by a coin of the large size to the full extent permitted by the slot and pin the forward part of the upper or operative edge comes to lie flush with the upper surface of the transversely disposed part and the rear part of the said edge curves upwardly with a curvature and in a position that will permit the retention of the large coin within the coin pocket.

An extension k^5 of the element below the pivotal point and the slot k^2 serves to carry a pin k^6 which extends outwardly through the adjacent wall of the coin holder through a slot d^2 which follows approximately a curvature struck about the pivotal point of the movable or ejector element as a centre and of a width to accommodate the movement of the pin projecting therethrough resulting from the movement of the penny striker g on the insertion of a penny into the corresponding coin pocket or coin space. The said pin serves for the connection of a helical tension spring l , the free end of which is anchored to a pin l^1 disposed towards the upper end and on the outside of the adjacent wall d of the coin holder. The action of the spring thus serves normally to maintain the movable or ejector element k in its uppermost position in which the lower end of the slot k^2 therein engages the cooperating pin k^3 carried by the transversely disposed part g^4 of the penny striker and in which the upper or operative edge k^4 of the movable or ejector element k is now disposed as an inclined or curved surface extending upwardly in the interior of the coin pocket. Thus, on the introduction of a shilling or a coin smaller than a penny, the movable or ejector element is not depressed to the extent necessary to bring the forward part of the operative or upper edge flush with the transversely disposed part of the penny striker and thus by the action of the spring l the element is returned to its upper position with the consequent ejection of the coin. When, however, a penny or the coin for which the slot is intended is introduced into the coin pocket of the coin space, the element is depressed to the extent that the upward reaction is diametrically opposed to the pressure exerted upon the coin by the casing of the coin holder. The coin is thus in a stable position and no tendency exists for its ejection.

Since the action of the helical tension spring l is to raise the movable or ejector element to its uppermost position in which the pin k^3 engaged in the slot k^2 of the element is disposed at the lower end of slot, the spring serves also for the purpose of maintaining the penny striker g in the uppermost position.

The transversely disposed part f^3 of the shilling striker f^2 is also provided on the outer side with an upwardly extending wall f^4 serving to define the corresponding wall of the penny coin pocket or coin space, the said upwardly extending wall having an inclined inner face to permit the shilling or like small coin when introduced into its slot to tilt over in the operation of the coin holder so that its upper or outer edge may occupy

substantially the same position as that of a penny or corresponding coin disposed in the penny coin pocket or coin space. At its forward end, also, the transversely disposed part f^3 of the shilling 5 striker is advantageously recessed to receive a roller f^5 which facilitates the entry of a coin into the corresponding coin pocket or recess.

In the modified construction represented in Figures 4 and 5, the insertion into a particular 10 slot of a coin smaller than that for which the slot is intended is prevented by constraining the movable element against pivotal movement until it has first moved a distance parallel to itself which is greater than that through which the smaller 15 coin accidentally inserted into the slot can move it. In order, according to the invention, that the movable element k may be constrained at the first to follow a path of movement parallel to itself or parallel with the coin holder disc b , the lateral 20 wall d of the coin holder adjacent the pivotal axis of the movable element is cut away or slotted to provide a guiding surface d^3 , which, for example, for the part that lies above the normal position of the pivotal axis of the movable element k , is 25 parallel with the coin holder disc b , and below the said axis is formed to clear an arc struck from the pivotal axis of the movable element as a centre when the said axis is in its lowermost position as 30 determined by the introduction of a coin of the correct size into the coin pocket. The slot d^2 in the lateral wall d is increased in width in a direction parallel with the coin holder disc b to permit of the movement of the element k parallel to itself. The movable element is provided with a 35 stop pin k^7 disposed above the pivotal axis, which pin contacts with and is constrained in movement by the guiding surface or slot before referred to.

In the operation of the ejector mechanism, on the insertion into the coin pocket of a coin of less diameter than that for which the coin pocket 40 is intended, the movement of the ejector element k and the corresponding striker plate g in a direction parallel with the disc b of the coin holder is insufficient to carry the stop pin k^7 of the ejector 45 element to the end of the guiding surface or slot d^3 which is disposed parallel with the disc of the coin holder, and thus the ejector element is constrained from rotation about its pivotal axis. The coin is therefore inoperative to effect rotation of the movable or ejector element and is prevented from fully entering into the coin pocket.

When a coin of the correct diameter is introduced into the coin pocket the ejector element k is moved to an extent which carries the stop pin 50 k^7 into a position out of contact with that part of the guiding surface or slot d^2 which is parallel with the coin holder disc b and into proximity with that portion of the guiding surface or slot which is struck as an arc d^3 about the pivotal 55 axis of the ejector element. The stop pin k^7 is thus free to revolve about the pivotal axis, and under the pressure of the advancing coin the ejector element is rotated about its axis until the force exerted by the helical spring l is applied 60 in the direction of the diameter of the coin which lies parallel with the coin holder disc. The coin is thus retained within the coin holder.

In the modified construction represented in Figure 6 the movable element k is provided with a 65 stud k^8 mounted in position adjacent the edge formed as a circular arc, which stud is permitted to extend through a suitable slot d^4 provided in the wall d of the coin holder casing and of a form to permit the movement of the stud k^8 following the 70 movements of the movable element. In an ad-

jacent position upon the wall of the coin holder casing there is mounted a stop member m in the form of a pawl conveniently pivoted upon the stud l^1 to which the helical spring l is anchored and of a curved form such that it extends in the one direction from the anchorage stud l^1 with clearance around the stud k^8 upon the movable element k and downwardly along the edge of the slot d^4 in the wall of the casing to a position at which it is required that the stud k^8 upon the movable element should be arrested. The stop element m is at this point provided with a projection or tooth m^1 extending inwardly into the path of the stud k^8 upon the movable element so that when the movable element is caused to rotate partially about its pivotal axis, the stud k^8 is arrested by the said projection or tooth m . The stop member m is bounded in the other direction from the anchorage stud l^1 by an angular or curved edge or edges m^2 which by contacting with a suitable surface, such as the inner surface of the carrier disc b of the coin holder or a mounting lug of the coin holder casing, determines the extent of angular or pivotal movement to be permitted to the stop member m . The stop member m is further mounted under the action of a spring m^3 conveniently provided upon the anchorage stud l^1 tending to move it always in the direction in which the projection or tooth m^1 extends into the path of the stud k^8 of the movable element, while permitting the stop element to be moved in the opposite direction out of the path of the stud. Thus, when, in the manner hereinafter described, the movable element k is moved to a position in which the stud k^8 has escaped from the stop member m , in the return movement of the movable element the stud k^8 is permitted to press the projection or tooth m^1 of the stop member m aside to pass upwardly to the initial position. To facilitate this action the edge of the projection or tooth m^1 is 30 suitably inclined to the direction or path of movement of the said stud k^8 .

In the operation of the mechanism, on the accidental insertion into the coin slot of a coin of a size smaller than that for which the coin 40 is intended, the pressure of the coin upon the movable element k causes the partial rotation of the latter to the position in which the stud k^8 thereon is arrested by the projection or tooth m^1 of the stop member m . The coin is thus 45 prevented from fully entering the slot and when released is rejected from the slot by the return movement of the movable element k under the action of the helical spring l .

When a coin of the size for which the coin 50 pocket is intended is pressed into the slot, the contacting of one portion of the edge of the coin with the outer end of the slot causes the oppositely disposed portion of the edge of the coin to press upon the movable element k at a position 55 adjacent to and in front of the pivotal axis. By the pressure thus exerted the striker g is moved downwardly in the coin holder casing in the direction to engage the measuring wheel h and at the same time the movable element k is also 60 carried downwardly to an extent which carries the stud k^8 thereon to a position in relation to the projection or tooth m^1 of the stop member m , such that the stud k^8 may pass in front of the said projection or tooth m^1 , if necessary by reason of a 65 small movement of the stop member m^1 against the action of its spring m^3 . The striker g being then arrested at the limit of its movement and in engagement with the measuring wheel h , the movable element k is permitted, under the pres- 70

sure of the coin to continue its movement in relation to the striker until it has passed into the position in which the slightly convex edge is presented to the coin in a position substantially 5 normal to the slot. The coin is thus retained within the coin pocket of the coin holder between the movable element k and the wall of the enclosing casing j . Upon the completion of the 10 rotation of the coin holder and the ejection of the coin into the coin container, the striker g and the movable element k return to the initial position under the action of the helical spring l , the stud k^8 of the movable element k pressing the projection or tooth m^1 of the stop member m 15 aside for the purpose.

Should a coin of a size smaller than that for which the coin pocket is intended be deliberately inserted into the slot, that is to say, should for example, a half-penny be deliberately inserted 20 into a slot intended for a penny by pressure applied through the coin upon the movable element k adjacent the pivotal axis the movements of the striker g and of the movable element k , such as hereinbefore described for the coin of 25 the correct size, may be carried out so that the improper coin is retained within the coin holder pocket. Having regard, however, to the smaller diameter of the improper coin, under the action 30 of the helical spring the striker g and the movable element k come to rest in a position in which the striker fails to engage the measuring wheel h . Thus, on the rotation of the coin holder, while the coin is retained and delivered into the coin 35 container, no measuring operation is effected and no supply of the commodity is secured.

The invention may be carried out in various ways and may be applied to coin holders provided with a single coin pocket and co-operating with a single coin slot, or to coin holders provided with 40 a plurality of coin pockets co-operating with a corresponding plurality of coin slots, whether such coin holders are applied to gas meters, electric meters or other like mechanisms.

It will be understood that the invention is not 45 limited to the details of construction hereinbefore described, since these may be varied without departing from the scope of the invention as hereinbefore set forth. Thus, in the second construction hereinbefore described, the movable element 50 may be mounted for a movement parallel to itself by means of co-operating pins and slots provided respectively on the movable member and in a surface which is stationary relatively thereto, or vice versa and the necessary rotational movement following the parallel movement may be effected by 55 extension of one of the slots in one direction along a curved path which is struck as the arc of a circle about the oppositely disposed pin. In the case where the movable element is provided to be 60 pivotally carried upon a striker plate or like member, the constraint imposing a movement parallel to itself followed by a rotary movement may also be effected in various ways. Thus, a pin disposed upon the movable element in determined relation 65 to the pivotal axis may co-operate with a cam or guiding surface formed upon an adjacent relatively stationary member. Alternatively, the pin may be carried by the stationary member and the cam or like surface be formed upon the movable 70 element. Again, the movable element may be provided with a slot of suitable rectilinear form extending at one end into the form of an arc, and such slot may co-operate with a pin in the relatively stationary member. Again, the relatively 75 stationary member and the movable element may

each be provided with cam-like surfaces which are formed to impose the required constraint of movement upon the movable element, or the pivotal pin of the movable element may be provided with an extension of rectangular or other angular form which may be constrained to move in a slot of corresponding form in the relatively stationary member, which slot is enlarged at one end into a circular form to permit rotation of the pivotal pin when centrally disposed in the said circular portion of the slot.

In the construction involving a stop member, while this is advantageously provided in the form of a pawl or catch mounted under spring action and having a determined normal position in 15 which it is adapted to restrain the movable element in its movement, other forms of stop member may be provided such, for example, as a plunger of suitable form subjected to spring action in such manner that on the return movement of 20 the movable element the plunger may be pressed out of the path of the movable element, or a slotted plate which is mounted under spring action permitting its movement from the normal position in relation to the coin holder. The movable element may be provided of such form as 25 directly to engage with the stop element, or it may carry a pin or like projection adapted for the purpose.

We claim:

1. In coin actuated mechanism for gas and similar meters and other like mechanisms, in which coins inserted into a coin holder are retained by pressure exerted in a direction transverse to that of the movement of the coin entering 35 the coin pocket of the coin holder, which coin actuates an operating member, the combination with a coin holder having a coin pocket, and a coin-actuated operating member, of an element positioned within the coin pocket and presenting 40 a coin-engaging surface through which pressure is directly applied to the coin in the coin pocket, means connecting the said element with the operating member such that the element has a rotational movement of limited range independent 45 of the movement of the operating member, and a spring for exerting through the said element pressure upon a coin within the coin pocket, the said element being so formed that the coin-engaging surface normally occupies a position inclined or 50 transverse to the path of entry of the coin into the coin pocket, such that a coin of the size for which the coin pocket is intended, in entering the coin pocket, will rotate the element into a position to apply pressure to maintain it in the coin pocket 55 and will move the operating member into an operative position, while a coin of a smaller size will fail to depress the element into the position for retention and will fail to move the operating member into the operative position.

2. In coin actuated mechanism for gas and similar meters and other like mechanisms, a coin holder having a coin pocket, a spring-controlled operating member which is depressed against the action of the spring by a coin introduced into the 65 coin pocket, the coin being retained in the coin pocket by reactionary pressure of the operating member, an element positioned within the coin pocket and presenting a coin-engaging surface through which the pressure is directly applied to 70 the coin in the coin pocket, which element is connected to the said operating member for imparting movement thereto and is mounted within the coin holder and in relation to the operating member for a rotational movement of limited range inde- 75

pendent of the movement imparted to the operating member, the said element being so formed that the coin-engaging surface normally occupies a position inclined or transverse to the path of entry of the coin into the coin pocket, such that a coin of the size for which the coin pocket is intended, in entering the coin pocket, will rotate the element into a position to apply pressure to maintain it in the coin pocket and will further cause the element to impart an operative movement to the operating member, while a coin of a smaller size will fail to depress the element into the position for retention and will fail to move the striker into the operative position.

3. In coin actuated mechanism for gas and similar meters and other like mechanisms, a coin holder having a coin pocket, an operating member which is moved into an operative position by a coin of determined size introduced into the coin pocket, a coin-engaging element positioned within the coin pocket and mounted in relation to the coin holder for a rectilinear movement in a direction transverse to the path of entry of the coin into the coin pocket and a rotational movement independent of the rectilinear movement, means connecting the element with the operating member whereby the element may carry the operating member with it in the rectilinear movement, and a spring acting upon the element to exert the pressure upon a coin in the coin pocket, the said element being so formed that its coin-engaging surface normally occupies a position inclined or transverse to the path of entry of the coin into the coin pocket, such that a coin of the size for which the coin pocket is intended, in entering the coin pocket, will rotate the element into a position to apply pressure to maintain it in the coin pocket and will further cause the element to impart an operative movement to the operating member, while a coin of a smaller size will fail to depress the element into the position for retention and will fail to move the striker into the operative position.

4. In coin actuated mechanism for gas and similar meters or other like mechanisms, a coin holder having a coin pocket, an operating member which is moved into an operative position by a coin of determined size introduced into the coin pocket, a coin-engaging element positioned within the coin pocket and mounted in relation to the coin holder for a rectilinear movement in a direction transverse to the path of entry of the coin into the coin pocket and a rotational movement independent of the rectilinear movement, means connecting the element with the operating member whereby the element may carry the operating member with it in the rectilinear movement, co-operating constraining elements provided respectively upon the element and upon the coin holder for limiting the rotational movement of the element except when the rectilinear movement is executed, and a spring acting upon the element to exert the pressure upon a coin in the coin pocket, the said element being so formed that its coin-engaging surface normally occupies a position inclined or transverse to the path of entry of the coin into the coin pocket, such that the coin of the size for which the coin pocket is intended, in entering the coin pocket, will rotate the element into a position to apply pressure to maintain it in the coin pocket and will further cause the element to impart an operative movement to the operating member, while a coin of a smaller size will fail to depress the element into the position for retention and will fail to move the striker into the operative position.

the position for retention and will fail to move the striker into the operative position.

5. In coin actuated mechanism for gas and similar meters or other like mechanisms, a coin holder having a coin pocket, an operating member which is moved into an operative position by a coin of determined size introduced into the coin pocket, a coin-engaging element positioned within the coin pocket and mounted in relation to the coin holder for a rectilinear movement in a direction transverse to the path of entry of the coin into the coin pocket and a rotational movement independent of the rectilinear movement, means connecting the element with the operating member whereby the element may carry the operating member with it in the rectilinear movement, co-operating constraining elements provided respectively upon the element and upon the coin holder for preventing the rotational movement of the element except when the rectilinear movement is executed, and a spring acting upon the element to exert the pressure upon a coin in the coin pocket, the said element being so formed that its coin-engaging surface normally occupies a position inclined or transverse to the path of entry of the coin into the coin pocket, such that the coin of the size for which the coin pocket is intended, in entering the coin pocket, will rotate the element into a position to apply pressure to maintain it in the coin pocket and will further cause the element to impart an operative movement to the operating member, while a coin of a smaller size will fail to depress the element into the position for retention and will fail to move the striker into the operative position.

6. In coin actuated mechanism for gas and similar meters, in which coins inserted into the coin holder are retained by pressure exerted in a direction transverse to that of the movement of the coin entering the coin pocket of the coin holder, which coin actuates a movable striker to engage a measuring wheel, the combination with a coin holder having a coin pocket, and a striker, of an element positioned within the coin pocket and having a coin-engaging surface through which the pressure is directly applied to a coin in the coin pocket, means connecting the said element with the striker such that the element has a rotational movement of limited range independent of the movement of the striker, and a spring for exerting through the said element the pressure upon a coin within the coin pocket, the said element being so formed that the coin-engaging surface normally occupies a position inclined or transverse to the path of entry of the coin into the coin pocket such that a coin of the size for which the coin pocket is intended, in entering the coin pocket, will rotate the element into a position to apply pressure to maintain it in the coin pocket and will move the striker into the operative position, while a coin of a smaller size will fail to depress the element into the position for retention and will fail to move the striker into the operative position.

7. In coin actuated mechanism for gas and similar meters, comprising a rotatable coin holder having a coin pocket, a striker mounted in the coin holder for movement in a direction transverse to the axis of rotation, and a spring retaining the striker in an inoperative position such that a coin of determined size inserted into the coin pocket of the coin holder depresses the striker into engagement with a measuring wheel and the coin is retained by the pressure of the striker exerted in a direction transverse to the axis of

rotation, an element pivotally mounted upon the striker for movement in a plane parallel to the plane of movement of the striker and subjected to the action of the spring, and means for limiting the pivotal movement of the said element, the said element being so formed as to present a surface inclined or transverse to the path of entry of a coin into the coin pocket such that a coin of the size for which the coin pocket is intended, in entering the coin pocket, will rotate the element into a position to apply pressure to maintain it in the coin pocket and will move the striker into the operative position, while a coin of a smaller size will fail to depress the element into the position for retention and will fail to move the striker into the operative position.

8. In coin actuated mechanism for gas and similar meters, comprising a rotatable coin holder having a coin pocket, a striker mounted in the coin holder for movement in a direction transverse to the axis of rotation, and a spring retaining the striker in an inoperative position such that a coin of determined size inserted into the coin pocket of the coin holder depresses the striker into engagement with a measuring wheel and the coin is retained by the pressure of the striker exerted in a direction transverse to the axis of rotation, an element pivotally mounted upon the striker for movement in a plane parallel to the plane of movement of the striker and subjected to the action of the spring, co-operating constraining elements provided respectively upon the element and upon the coin holder for preventing the pivotal movement of the said element until movement of the striker has been effected, and means for limiting the pivotal movement of the said element, the said element being so formed as to present a surface inclined or transverse to the path of entry of a coin into the coin pocket such that a coin of the size for which

the coin pocket is intended, in entering the coin pocket, will rotate the element into a position to apply pressure to maintain it in the coin pocket and will move the striker into the operative position, while a coin of smaller size will fail to depress the element into the position for retention and will fail to move the striker into the operative position.

9. In coin actuated mechanism for gas and similar meters, comprising a rotatable coin holder having a coin pocket, a striker mounted for movement in the coin holder in a direction transverse to the action of rotation, and a spring retaining the striker in an inoperative position such that a coin of determined size inserted into the coin pocket of the coin holder depresses the striker into engagement with a measuring wheel, an element pivotally mounted upon the striker for movement in a plane parallel to the plane of movement of the striker, means for limiting the pivotal movement of the said element which is so formed and mounted under the action of the spring as to present a coin-engaging surface inclined or transverse to the path of entry of a coin into the coin pocket, and a catch resiliently mounted upon the coin holder and engaging the element to arrest the pivotal movement of the element when effected in the absence of the movement of the striker, so that a coin of the size for which the coin pocket is intended, in entering the coin pocket, will depress the element and the striker to the extent to free the element of the control of the catch and will rotate the element into a position to apply pressure to maintain it in the coin pocket, while a coin of a smaller size will fail to depress the element to free it from the catch and will fail to move the striker.
